UNITED STATES PATENT OFFICE.

MORRIS LEVITAN, OF NEW YORK, N. Y.

DESIGN FOR A BULB RETAINER FOR ELECTRIC-LIGHTING FIXTURES.

Application filed May 12, 1926. Serial No. 17,672. Term of patent 3½ years.

To all whom it may concern:

Be it known that I, MORRIS LEVITAN, a citizen of the United States, residing at No. 868 Faile Street, borough of Bronx, city and State of New York, have invented a new, original, and ornamental Design for a Bulb Retainer for Electric Lighting Fixtures, of which the following is a specification, reference being had to the accompanying drawing, forming a part thereof.

The figure shows a perspective view of my new design for a bulb retainer for electric lighting fixtures, as shown.

I claim:

The ornamental design for a bulb retainer for electric lighting fixtures, as shown.

MORRIS LEVITAN.
